FLOYD W. PRIESTLY, OF STOCKTON, CALIFORNIA, ASSIGNOR OF ONE-HALF TO DR. S. F. PRIESTLY, OF STOCKTON, CALIFORNIA.

BANDAGE-ROLL CUTTER.

1,146,098.

Specification of Letters Patent. Patented July 13, 1915.

Application filed November 5, 1914. Serial No. 870,541.

To all whom it may concern:

Be it known that I, FLOYD W. PRIESTLY, a citizen of the United States, residing at Stockton, in the county of San Joaquin,

5 State of California, have invented certain new and useful Improvements in Bandage-Roll Cutters; and I do declare the following to be a full, clear, and exact description of the same, such as will enable others 10 skilled in the art to which it appertains to make and use the same, reference being had to the accompanying drawings, and to the characters of reference marked thereon, which form a part of this application.

15 This invention relates to improvements in a bandage roll cutter and is adapted for use wherever it is necessary to use bandages to any extent. The roll of bandage being in a wide roll it is often desirable, to avoid 20 waste and an unnecessary amount of bandaging, to have the bandage of a certain width as demanded by the wound or hurt being treated, and to this end I have produced my improved device.

25 A further object of the invention is to produce a simple and inexpensive device and yet one which will be exceedingly effective for the purposes for which it is designed.

These objects I accomplish by means of 30 such structure and relative arrangement of parts as will fully appear by a perusal of the following specification and claims.

In the drawings similar characters of reference indicate corresponding parts in the 35 several views.

Figure 1 is a top plan view, partly broken out, of the device. Fig. 2 is a side view of the device. Fig. 3 is an end view of the device.

40 Referring now more particularly to the characters of reference on the drawings, the numeral 1 indicates a rectangular metal base plate to which I have riveted four upright round knife guide posts 2 placed in 45 pairs on opposite sides of the base plate with a slight opening 3 between as clearly shown in the drawing.

The roll of bandage is placed in the holder 50 formed by the upright clamp members 4 and 5. The clamp 4 being held stationary and the clamp 5 being made slideable, permits a quick adjustment to any size roll of bandage. To hold the clamp 4 stationary I have cut slots in the base portion thereof 55 and placed machine screws 6 running up

through the projecting portions 4^a into a light plate 7 running the full length of the clamp and forming a part of the stationary member of the slide. The clamp 5 has in the base portion thereof, slots cut opposite to those of the slots in the clamp 4 thereby forming the projections 8 which are adapted to slide in the slots of the clamp 4 and to be held in place by the stationary plate 7. The slideable clamp 5 when pushed up against the roll of bandage will hold itself firmly in place as the upright portion 5 being pushed outwardly will tend to raise the projections 8, at right angles thereto, upward against the plate 7 thereby holding the same in frictional contact therewith to prevent the clamp 5 from sliding too easily out of position.

Upon the base plate 1 and between the posts 2 I have fastened a piece of fiber 9, 75 which will act as a guard against the edge of the knife coming into contact with the metal base plate.

To provide a convenient method of measuring the width of the roll of bandage to 80 be cut I have provided a rule 10 dovetailed into the base plate and slideable therein.

To cut the bandage the desired width the bandage is projected past the posts 2 and then cut off by using any kind of knife in 85 the slot 3 formed by the guide posts 2.

From the foregoing description it will be readily seen that I have produced such a device as substantially fulfills the object of the invention as set forth herein.

While this specification sets forth in detail the present and preferred construction of the device, still in practice such deviations from such detail may be resorted to as do not form a departure from the spirit 95 of the invention, as defined by the appended claims.

Having thus described my invention what I claim as new and useful and desire to secure by Letters Patent is:

1. A device of the character described comprising the combination with a base plate, of vertical spaced guides mounted on said plate, a fixed clamp member mounted on said plate adjacent said guides, and another clamp member slideably mounted to be moved toward or away from said fixed clamp member whereby the bandage roll may be clamped therebetween and project between said guide members, as described. 110

2. A device of the character described comprising a base plate provided with vertical guide members spaced apart, a rule 5 slidably mounted in said base plate, the upper face of the rule being flush with the upper face of said plate, an adjustable clamp structure disposed on said plate and extending longitudinally with respect to said rule, said clamp member being adapted to engage 10 the bandage roll, such bandage roll being adapted to extend longitudinally with respect to said rule and between said guide members, as described.
3. A device of the character described 15 comprising the combination with a base plate, of a fixed stationary clamp member having a projecting base provided with slots, a slidable

clamp member having a base provided with slots forming projections slidably disposed within the slots in the base of the fixed 20 clamp member, and a plate resting on the base members of said clamp members and secured to said base plate whereby said projections on the base of said movable clamp may slide thereunder, and vertical guide 25 members disposed adjacent said clamp structure, as described.

In testimony whereof I affix my signature in presence of two witnesses.

FLOYD W. PRIESTLY.
